UNITED STATES PATENT OFFICE.

WILLIAM C. FINCK, OF ELIZABETH, NEW JERSEY, ASSIGNOR TO SANFORD HUNT AND HOMER EATON, OF NEW YORK, N. Y.

DESIGN FOR A BADGE.

SPECIFICATION forming part of Design No. 24,043, dated February 19, 1895.

Application filed October 31, 1894. Serial No. 527,579. Term of patent 14 years.

To all whom it may concern:

Be it known that I, WILLIAM C. FINCK, a citizen of the United States, residing at Elizabeth, Union county, New Jersey, have invented a certain new and original Design for Badges, fully described and represented in the following specification and the accompanying drawing, forming a part of the same.

The leading feature of my design consists in a Maltese cross forming a background for a ring of interwoven thorn branches, having the appearance of being laid thereon to hide the junction of its arms, such branches being suitably bent and intertwined to form a circular series of substantially round spaces each for the reception of one of the letters of a suitable motto, and the whole inclosing the representation of a rectangular cross.

In the annexed drawing, the cross *a* is shown provided upon its body portion with the in-

tertwined thorn branches *b* having projecting thorns *b'* at intervals, the branches being so curved and crossed upon each other as to form a series of circular spaces *c*. A cross *e*, of that form having the cross-piece arranged ²⁵ above the center and perpendicular to the upright stem, is disposed within the center of the said ring.

Having thus set forth the nature of the design, what I claim herein, and desire to secure ³⁰ by Letters Patent, is—

The design for a badge herein shown and described.

In testimony whereof I have hereunto set my hand in the presence of two subscribing ³⁵ witnesses.

WILLIAM C. FINCK.
